SCANNING APPARATUS

Charles J. Young, Ardmore, Pa., assignor to
 Radio Corporation of America, a corporation
 of Delaware

Application April 29, 1942, Serial No. 440,923

12 Claims. (Cl. 178—7.1)

My invention in general relates to apparatus for the transmission and reception of intelligence, and more particularly to a form of facsimile apparatus.

A number of differing types of facsimile scanners have been known and suggested in the prior art, and by the term scanner is included receiving means as well as transmitting means. Popular amongst the previously known scanners is an arrangement whereby the material to be transmitted is placed on a rotating drum, and either the drum is traversed with respect to the pick-up unit, or vice versa. Also, there are other arrangements in which relative motion between the scanning element and the scanned material is necessary, and heretofore where these elements have been inclosed it has resulted in a more or less inaccessible or awkward apparatus. Accordingly, it is one of the objects of my invention to provide an arrangement which, although entirely inclosed, and having no outwardly moving parts, is easily accessible, substantially dust tight, and otherwise desirable.

In the heretofore known prior art the scanning of material to be transmitted has been initiated by the engagement of a clutch member between the driving motor and the moving elements, or the scanning has been stopped for the purpose of adding material to be scanned to the moving elements by the disengagement of a clutch. This clutch naturally can be a source of great trouble since it must not only be accurate, but must be definitely energized with considerable force in order to insure accurate engagement. It is the object of the present invention to provide a device in which no clutch member will be necessary between the scanning drum and the driving means in a facsimile scansion apparatus.

Again, in the arrangements previously known to the prior art, and wherein the material to be scanned has been fastened into position, and wherein the signals developed depended on the reflection of light from the surface to be scanned onto photo-electric means, varying thicknesses of material containing the intelligence affected the correct focus of the lens systems associated with the pick-up or scanning unit. It is another of the objects of my invention to provide an apparatus in which the material to be scanned will, of necessity, be accurately and definitely focused with respect to the optical systems of the pick-up or projection means.

At the present time, facsimile apparatus has been found to be of considerable interest from

5 a military standpoint since, for instance, in the case of airplanes, it is preferable to be able to transmit materials such as maps, or even written intelligence and the like, from an observing plane to its base, rather than depend purely on photographs, since there is no definite assurance that the plane ultimately will return to its base, and where photographic means are used this means that a flight has been wasted, as well as a plane, unless the plane returns. On the other hand, by utilizing facsimile apparatus, the flight has not been rendered useless if the material can be transmitted from the plane at the time that it is picked up by the plane, whether the plane subsequently returns to its base or not. It will be appreciated that such apparatus necessarily must be not only accurate, but must be compact and rugged as well. Accordingly, it is one of the objects of my invention to provide a facsimile scansion apparatus which is highly adaptable for use for military purposes.

Other objects will be obvious from the hereinafter appended description, and it will be appreciated that the foregoing have been listed only 15 as indicative of some of the objects and purposes of the invention.

My invention in general contemplates the provision of a semi-cylindrical member about the periphery of which is held firmly against the face 20 thereof the material to be transmitted, or, in the case of a receiver, material on which the intelligence may be recorded. Placed so as to be partially embraced by the 180° cylinder is a rotating double optical system, which not only rotates with respect to the cylindrical surface, but also is caused to traverse along the axis of the semi-cylinder. Appropriate means are provided 25 for causing this optical system to direct a beam of light onto the material to be scanned, and in the case of a transmitter photo-electric means 30 are provided which will pick up light reflected from the surface which is scanned. Since a double optical system is provided, that is to say, since two optical systems 180° apart from each other 35 are provided, scanning is continuous despite the fact that the surface against which the intelligence is held is a 180° semi-cylinder. The driving means for causing the optical systems to rotate as well as traverse are mounted and travel 40 along with the optical systems, although it will be appreciated that separate driving means might be used for rotating and traversing the optical systems. An appropriate pre-amplifier also is 45 provided and rides along with the optical systems during their traversal of the surface to be 50

scanned. In general, it has been found that the semi-cylinder, which is transparent, may be made advantageously of a plastic material such as Lucite, Crystallite, etc., rather than glass.

My invention will best be understood by reference to the drawings, in which:

Fig. 1 is a schematic showing of a device in accordance with my invention.

Fig. 2 is a partial illustration of a side view of a device utilizing my invention.

Fig. 3 is a view showing other details of a device according to my invention.

Fig. 4 is a partial view of a dual scanning unit.

Referring to Fig. 1, there is shown a schematic view of a device embodying the principles of my invention. In this view a semi-cylindrical transparent member 10 has placed in intimate contact with the outer surface thereof a planar material 11 on which is recorded the intelligence to be transmitted, and of which scansion signals are to be developed which are representative of the optical values thereof. Positioned so as to be in scanning relationship through the semi-cylindrical member 10 is a dual scanning arrangement contained within the rotatable element 12 which may also contain a pre-amplifier. In general, the scanning arrangement will comprise two complete scanning units disposed 180° apart with respect to each other and adapted to be rotated by rotation of the shaft 13. These scanning units each contain a light source with means for directing the light from the source through an aperture and through the transparent supporting member 10 onto the material to be scanned. Positioned adjacent the light source and having an optical system adapted to project light reflected from the surface of the image to be scanned is a photo-electric member and the reflected light may find its way to the directing optical system through another aperture. This arrangement will be shown schematically in somewhat greater detail in Fig. 3, and since such devices per se have been known heretofore, and since the particular arrangement of this device does not form the essence of this invention, the device need not be described in great detail.

For purposes of simplicity the means of energizing the various elements of the scanning unit have not been illustrated, as these means will be well known to those skilled in the art. By way of example, the lamp in each scanning unit might be energized by means of running the leads thereof to a pair of slip rings and impressing the necessary voltage and current onto the slip rings to light the lamp. Similarly, the biasing voltage for the photo-electric cells might be impressed in the same manner. Such means are well known to those skilled in the art, and do not need elaboration.

The shaft 13 is connected to a gear 20, the gear being driven by the worm 21, the latter being rotated by means of motor means 22. The worm 21 also rotates a gear 23 which is joined through a shaft 24 to worm 25, the latter meshing with gear 26. The gear 26 is fixed on a shaft containing an elongated lead screw 27. There has been shown as partially broken away a housing 30, the purpose of which is to act as a mounting means for the motor 22, the lead screw 27, the gear 20, the associated dual scanning arrangement 12, and a pre-amplifier 100. The housing with these elements is supported in

such a manner that the housing can be moved along in the device with all of the elements recited, and such mounting means will be more fully illustrated in Fig. 2. The supporting housing 30 on which is mounted not only the driving motor means 22, but the supports for the dual scanning apparatus having the casing 12 and also for the pre-amplifier 100, has been broken away in this figure for purposes of clarity. It will be appreciated, however, that the two sections which are identified by the numeral 30 relate to one and the same housing, part of which is illustrated in somewhat more detail hereinafter in Fig. 4.

Positioned adjacent the lead screw 27 is a half nut arrangement 33 which is fastened to a rotatable lever arm means 34, and at the end of the lever arm 34 remote from the half nut 33 there is positioned a lever arm 35 which is pivoted at 37 and joins the shaft 34 at the position 31. At the extremity of the arm 35 which is remote from the position 31 there is connected a spring means 38. Positioned in co-operative relationship with arm 35 is a second pivoted lever arm 40 which is pivoted at the point 41, and which also has fastened to the end thereof the spring 38. Substantially at the end of lever arm 40 remote from its connection to the spring 38 is a push button or lever means 42 which contains a slot through which passes the lever arm 40.

Positioned in co-operative relationship with the lever arm 40 is a third lever arm arrangement 50 which is pivoted at the point 51. A substantially L shaped section of this third lever arm has the lower portion thereof running under the lever arm 40 and on the other side of the pivot 51 this lever arm continues and forms two L shaped members having a common arm, with the other two sections thereof being positioned substantially at right angles each to the other to form a substantially L shaped arrangement. Fastened to the housing 30 is an arm 55. Also fastened to the housing 30 is a pin 56 to which is joined a flexible member 57 which in turn is joined to a take-up spring arrangement partially illustrated at 58.

The action of the device is as follows. The transparent member 10 is always maintained in a fixed position, and the entire arrangement is mounted within a substantially light tight housing. It will be apparent, therefore, that there are no moving parts to the outer portion of the machine which may be struck or interfered with in any fashion during operation of the machine. Since the member 10 is a semi-cylinder, the material to be scanned may be merely placed over the semi-cylinder and a cover drawn over it, and thus there is complete accessibility in either placing or removing material to be scanned from the device. In this illustration the scanning takes place along a line which travels from right to left in the drawings. If it be assumed that the machine is at the starting position and operation is desired, the button on the lever arm 42 is pushed downwardly. This causes the opposite end of the lever arm 40 to move upwardly and the lever arm 40 has joined to the end thereof a spring 38 which is maintained in compression. This means that when the arm 40 moves upwardly past the center point the spring 38 will force the portion of lever arm 35 to which it is fastened downwardly very sharply. Since the lever arm 35 is pivoted at 31 and 37 this means that the shaft 34 will rotate and will bring half

nut 33 into engagement with the lead screw 27. Since it has been indicated hereinbefore that the driving element and the scansion means and the pre-amplifier all are mounted on a housing or holder or support, it will be appreciated that as the lead screw co-operates with the half nut member, the housing 30 will be traversed along the semi-cylindrical transparent member 10 and scanning will take place by the action of each scanning unit of the two scanning units which are displaced 180° with respect to each other, as it passes adjacent the semi-cylindrical member 10. The dual scanning units will be illustrated more clearly hereinafter in Fig. 4, and accordingly there will be stated at this point that the bottom portion of the machine has contained therein a non-reflecting, light absorbing member so that while one portion of the scanning unit is traversing this particular portion of the machine, no signals will be developed in the photoelectric cell. As a result thereof, a commutating arrangement is avoided, and the advantages of a dual scanning arrangement are provided. As the housing 30 moves along due to the engagement of lead screw 27 with the half nut 33, it will gradually reach a position where arm 55 will come into contact with a portion of lever arm 50, as illustrated. When this is done, this lever arm will be rotated around the pivot 51 and the L shaped portion of the arm co-operating with lever 40 will be forced upwardly, thus turning lever arm 40 about its pivot point 41 so that the end thereof adjoining spring 38 will be forced downwardly. When this is done the arm 40 will pass the center or neutral position of the spring 38, and when it does the portion of the lever arm 35 joined to the spring 38 will be forced upwardly sharply. This means that the shaft 34 will be rotated and the half nut 33 will be removed from engagement with the lead screw 27. When the half nut 33 is removed from engagement with the lead screw 27, the housing 30, which was previously moved against the tension of the spring in member 58, will be drawn back to its initial scanning position by the action of the spring in member 58.

In the actual arrangement the pre-amplifier has been mounted on the housing or support 30 along with the other elements which have been stated as being supported thereby, and has been an entirely separate unit and has been energized by the output light reflected from the object undergoing scansion. Since such preamplifiers per se are well known, and since well known forms may be used, it is entirely within the skill of persons practiced in the art to which this invention belongs to construct and use and correctly connect such pre-amplifying arrangements.

Also, it will be appreciated that while the supporting means or elements such as the lead screw 27 have not been shown in this figure, it is well within the skill of persons who practice the art to which this invention belongs to provide bearing means on the supporting housing to accommodate the lead screw at either end thereof.

Nor has there been illustrated in this figure any means for making the device operate continuously until it is shut off, but the arrangement as shown indicates that scanning has been initiated by pressing the button attached to the lever arm 42 downwardly, which causes the engagement of the half nut 33 with the lead screw 27. Then one complete scanning takes place and when the support member reaches the position shown in the figure, the lever arm 50 will be actuated as ex-

plained hereinbefore to remove the half nut 33 from its engagement with the lead screw 27 and the support member is pulled back to a position where scanning can start again. It is entirely feasible, however, to make the device completely automatic. A lever arm might be arranged to contact with a member such as the member 55 on the support or housing 30 so that when the spring member pulls the support back to its initial position, the lever arm could be actuated to move the half nut arrangement into engagement with the lead screw 27, and again scanning would take place and the cycle would be repeated. This might be accomplished, for instance, by having a slightly tilted member to push gradually downwardly against a lever arm joined directly to the shaft 34. On the other hand, one contact of a switch arrangement could be mounted on any of the traveling members supported by the support 30, and the other contact mounted at an appropriate place to close an electrical circuit when the support is returned to its starting position. Closure of the circuit could actuate the armature of a solenoid, this armature acting to push or pull the half nut arrangement into engagement with the lead screw 27. This might be done in other ways, but the two examples given are illustrative.

Referring to Fig. 2, there is shown a portion of the support member 30 which illustrates the mounting of some parts thereof. A cross-sectional view of the container for the whole apparatus is shown to illustrate the general working arrangement. Here the shaft 13 ends in a bearing in a gear box housing 60 and the motor 22 is mounted under the base 61 of the support member 30 by means of an appropriate bracket arrangement 62. The shaft 24 which ends in a worm 25 co-acting with the gear 26 fastened to the lead screw is illustrated, and bearing means 63 are illustrated as joined to the base plate 61 of the housing 30 for supporting the lead screw 27. It will be noted that the base plate 61 has a sliding bearing arrangement 64 which fits around a guide rod 65, the guide rod being fastened at either end of the cabinet, or at other appropriate positions for the sake of supporting the traveling housing 30. Again, one side of the base plate 61 is cut in the form of a keyway 66 which fits onto a bracket member 67 and slides along the bracket, the bracket acting as a guide and support rod. In this instance, the guide is fastened to the wall 68 of the container. The semi-cylindrical transparent member is illustrated, as well as the member 12 containing the dual scanning arrangement and the pre-amplifier. Again, it should be noted that in actual practice the pre-amplifier is not contained in the member 12, but is fastened onto the base plate 61.

Referring to Fig. 3, there is shown a partial view of the apparatus that would be shown on a cutting plane transverse to the cabinet. In this view the shaft 13 is shown, as well as the member 12. The path of rotation and the general direction of rotation has been indicated by the dashed and dotted circle 14. The edges of the transparent semi-cylindrical member in this case are held between the edge 76 of the cabinet of the device and the bracket 71, so that this member does not move at all. The cover which allows accessibility to the semi-cylinder, and also holds the material in intimate contact with the semi-cylinder, is illustrated, and some parts are shown in detail. For instance, the outer section of the cover is formed of two sections 78 and 79, the two being

joined by an elongated hinge 80. Also joined to the cover is a resilient member 81 which is adapted to fit in intimate contact with the top of the semi-cylinder, and this member fits around a rod 82 and is held by one end of a spring member 83, the other of which is connected to the top at the position 84. It will be seen, therefore, that the further down that the cover is pulled, the more tension is placed on the member 81 by the action of the spring 83, and so the material which contains the intelligence to be transmitted is held in intimate contact with the top of the transparent semi-cylinder. This is a distinct advantage, since no matter how thick the material may be, the face thereof is always the same distance from the optical systems in the dual scanning elements, and hence focus is maintained at all times.

The subject matter of this particular arrangement forms the basis of another patent application, Serial No. 450,855, filed July 14, 1942, and accordingly is not claimed in the present case.

Referring to Fig. 4, there is shown a partial view of the apparatus with the dual scanning arrangement illustrated. The shaft 13 joins the housing 12 which contains therein a single source of light 92, and there is positioned so as to embrace this source of light two reflecting members 95, each of which has an aperture therein identified by the numeral 96. At each extremity of the housing 12 is a lens holder arrangement 94 containing the lens 93 for directing light from the source onto the object to be scanned which is identified by the numeral 11, the object being placed about the periphery of the 180° drum 10. Light from the object undergoing scansion will be reflected by means of reflectors 90 and 91 to the mirror arrangements consisting of the two elements 95, and from the mirror 95 onto the photoelectric cell 99, the latter being connected so as to feed its output energy into a well known form of pre-amplifying apparatus which is schematically represented at 100. The lower part of the apparatus has contained therein a non-reflecting material which allows one of the scanning units to direct light onto the object to be scanned and receive light therefrom in accordance with the optical values along the elemental sections thereof, while simultaneously the other scanning unit is positioned adjacent the light absorbing material so that no reflection takes place from the latter material, and the unit which is adjacent the light absorbing material at any time will be brought into a scanning relationship with the member 10 by the rotation of the shaft 13. Accordingly, no commutating means are necessary for the photoelectric cell, and in addition a single source of light has been provided for use with both ends of the dual scanning head. The figure brings out the fact that there is no reflection back through the aperture 98 when the scanning head is in the position illustrated.

The means for and method of centering the scanning elements relatively to the transparent plastic member 10 constitute very important means in conjunction with this apparatus, and accordingly are more particularly shown and disclosed in an additional patent application, Serial No. 450,856, filed July 14, 1942.

It will be appreciated that there may be departures from the particular showing which has been given in this invention without departing from the spirit and scope thereof, and accordingly I claim to be entitled to all such departures as fall fairly within the spirit and scope of the invention as defined in the hereinafter appended claims.

What I claim is:

1. A scanning apparatus for developing electrical signals from a record surface representative of the optical values of said surface, comprising a plurality of scanning elements, each for developing electrical signals, means for supporting said record surface in a position to be scanned, said latter means comprising at least a portion of a substantially cylindrical member, a light absorbing member positioned diametrically opposite the record surface supporting means, means for rotating said scanning elements about the axis of symmetry of the cylindrical member internally of said record surface while maintaining said record surface substantially fixed, and means for longitudinally moving the scanning elements and record surface relative to each other, whereby said record surface is linearly scanned by the sequential operation of said plurality of scanning means.

2. Apparatus in accordance with claim 1, wherein said plurality of scanning elements comprises a pair of individual scanning elements displaced apart from each other about the axis of rotation, and wherein each scanning element scans alternate lines of the record surface.

3. Apparatus in accordance with claim 1, wherein a single motor means is provided for rotating the scanning elements and for traversing the scanning elements longitudinally relative to the object to be scanned.

4. Apparatus in accordance with claim 1, wherein a single motor means is provided for rotating the scanning elements and for traversing the scanning elements longitudinally relative to the object to be scanned, and wherein said single motor means is mounted on a housing supporting the scanning elements and pre-amplifier means mounted on the same housing.

5. A scanning apparatus for developing signals from a record surface which are indicative of the optical values of said record surface, comprising means for supporting said record surface, said latter means comprising at least a partial cylinder, a plurality of rotatable scanning means spaced apart from each other and positioned adjacent said supporting member, means for rotating said scanning means about the axis of symmetry of said record support means, a non-reflecting surface positioned diametrically opposite said record support means, and means for traversing said scanning means longitudinally with respect to said record supporting member whereby the record surface is linearly scanned by each of the scanning means by means of the sequential scanning of the surface by the scanning means during their longitudinal traversal of the surface.

6. Apparatus in accordance with claim 5, wherein said plurality of scanning means comprises a pair of individual scanning members spaced apart from each other.

7. A scanning apparatus for developing signals from a record surface which are indicative of the optical values of said record surface, comprising means for supporting said record surface, said latter means comprising a substantially semi-cylindrical transparent member, means for holding the record surface in intimate contact with said semi-cylindrical member, a pair of rotatable scanning elements adapted to be rotated simultaneously, and spaced apart from each other, means for rotating said scanning elements about the longitudinal axis of the semi-cylindrical transparent member whereby each of the scanning elements scans a linear section of the record

surface sequentially with the other scanning element, a light absorbing surface located diametrically opposite the semi-cylindrical support member and in the vicinity of the scanning elements, and means for longitudinally traversing said scanning elements relative to the record surface during the rotation thereof whereby scansion is accomplished linearly and sequentially by said spaced apart scanning elements.

8. Apparatus in accordance with claim 7, wherein said rotatable pair of individual scanning elements are spaced apart from each other substantially 180° relative to their axis of rotation.

9. A scanning apparatus for developing signals from a record surface which are indicative of the optical values of said record surface, comprising means for supporting said record surface, said latter means comprising a substantially semi-cylindrical transparent member, a pair of rotatable scanning elements positioned adjacent said transparent support member, housing means, means for rotating said scanning elements about the longitudinal axis of said semi-cylindrical transparent member, lead screw means, means for driving said means for rotating said scanning elements and said lead screw means simultaneously, said means for rotating said scanning elements, said lead screw means, and said driving means all being mounted on and supported by said housing means, means for engaging said lead screw means whereby said housing means may cause the scanning elements to longi-

tudinally traverse the transparent support member while rotating adjacent thereto, whereby at least a portion of said record surface is linearly scanned sequentially by said rotating scanning elements, and light absorbing surfaces to substantially preclude the development of signals from the scanning elements except during the intervals that they are opposite the semi-cylindrical support means.

10. Apparatus in accordance with claim 9, wherein said means for engaging said lead screw means comprises a threaded member and wherein there is provided in addition means for actuating said threaded member to bring it into or out of engagement with said lead screw means.

11. Apparatus in accordance with claim 9, wherein means are provided for slidably supporting said housing, whereby the housing may cause the longitudinal traversal of the transparent support member by said rotating scanning elements.

12. Apparatus in accordance with claim 9, wherein said means for engaging said lead screw means comprises a threaded member and wherein there is provided in addition means for actuating said threaded member to bring it into engagement with said lead screw means, means for automatically disengaging said threaded member from said lead screw means, means for returning said housing member to an initial scanning position, and means for slidably supporting said housing.

CHARLES J. YOUNG.
